Attorney

UNITED STATES PATENT OFFICE.

ALBERT WOODALL SMITH, OF MANCHESTER, ENGLAND.

FILLING HEAD OF BOTTLE-FILLING MACHINES.

Application filed August 6, 1924, Serial No. 730,481, and in Great Britain August 18, 1923.

This invention relates to bottle filling machines of the counterpressure type in which the bottle is filled under pressure, the gas supply to the bottle being cut off and the 5 return gas port opened before the liquor is supplied thereto, and more particularly to such machines having a fixed disc with ports formed therein into which the gas and liquor supply tubes and the gas release tube from 10 the bottle project and having a disc with ports therein oscillating in contact with the fixed disc.

In one such arrangement two tubes are employed and the liquor port is carried 15 through the spindle on which the disc is mounted thereby necessitating a leather packing or gland around the spindle which is particularly objectionable when beer or similar liquid is being filled into the bottle.

20 The present invention consists in the combination of a stationary disc provided with a centrally arranged stem and with ports terminating in its outer face and located at substantially the same distance from said 25 stem, together with a second disc mounted to rotate on said stem in contact with the stationary disc and having grooves in its contacting face, which grooves, when the movable disc is partially rotated, bring the 30 gas and liquor ports in turn in communication with the bottle to be filled and on further partial rotation of said latter disk opening the snift port and returning the valve to its initial position.

35 The invention will be fully described with reference to the accompanying drawings.

Fig. 1 is a front elevation.

Fig. 2 is a side elevation partly in section.

Fig. 3 is a plan with oscillating disc removed.

40 Fig. 4 is a front elevation partly in section with oscillating disc removed.

Fig. 5 is a side elevation of oscillating disc.

45 A fixed disc A is formed with a series of ports a' , a'' , a^3 , a^4 , a^5 connected respectively to the gas supply inlet conduit b , the liquor inlet conduit b' , gas delivery and outlet pipe b^2 to the bottle, liquor delivery pipe b^3 , gas 50 return conduit b^4 and snift conduit b^5 open to the atmosphere. The disc A also has in its face an arcuate groove a^6 which has one of its ends connected to the gas delivery inlet and outlet port a^2 to the bottle.

55 The fixed disc A is carried by one of the rotary heads B on the bottling machine and

is formed with a central spindle A' upon which is mounted an oscillating disc C formed with three arms C' , C^2 , C^3 adapted to engage stationary rollers on the machine 60 as the head rotates to impart oscillatory movement to the oscillating disc C relatively to the fixed disc A. The face of the disc C is kept in close contact with the face of the disc A by means of a spring c bearing 65 against a washer a^7 secured to the spindle A' by a nut a^8 .

The oscillating disc C has in its face which contacts with the fixed disc A a groove c' , which, when the disc C is given a partial 70 rotation, is brought opposite to the liquor inlet port a' and the liquor outlet port a^3 of the disc A and thus establishes communication between said ports. The disc C also has in its face which contacts with the disc A a second groove c^2 which is arranged diametrically opposite to the groove c' and extends radially of the axis of rotation of the disc C. One end of the groove c^2 is always 75 opposite to and in communication with the arcuate groove a^6 of the disc A and its opposite end is adapted, when the disc C is rotated, to be brought opposite to the gas inlet port a or the gas return port a^4 or the snift port a^5 of the disc A. 80

The lower part of the revolving head is formed in the usual manner with a screwed cap D for receiving the lip of the bottle being filled. The liquor delivery pipe b^3 from the liquor outlet port a^3 of the stationary disc A is arranged to project below the cap D and into the bottle being filled. The gas delivery and outlet pipe b^2 from the port a^2 of the disc A is also arranged 90 to project into the bottle. 95

The liquor conduit b' to the liquor inlet port a' of the disc A communicates with the liquor reservoir and the gas conduit b to the gas inlet port a communicates with the gas cylinder, the return gas conduit b^4 100 to the return gas port a^4 also communicates with the gas inlet conduit b , while the snift pipe b^5 to the snift port a^5 of the disk A is in communication with the atmosphere. An adjustable screw b^6 is provided to vary 105 the size of the snift conduit b^5 , and metal ball valves b^7 and b^8 are inserted in the liquor and gas inlet conduits b' and b^4 —respectively to close said conduits should a 110 bottle burst.

The disc is oscillated by stationary rollers on the frame engaging one or other of the

arms C', C², C³ as the rotating head passes the rollers, the arms C', C², C³ being formed with cam surfaces of varying lengths according to the travel required for opening 5 or closing each of the ports of the disk A. When a bottle is placed in position all the ports in the disk A are closed with the exception of the snift port A⁵. The disc C is then rotated by the arm C² to put the 10 gas inlet port a in communication with the port a² through the two grooves a⁶ and c² (Fig. 1). The arm C' is then moved to close the port a and place the liquor inlet port a' in communication with the liquor 15 delivery port a³ through the groove c' and at the same time place the gas return port a⁴ in communication with the port a² through the grooves a⁶ and c². When the bottle is full the arm C³ is actuated to re- 20 turn the disk C to the closed position ready for filling a subsequent bottle and the filled bottle is removed.

A non-rotating disc or washer E provided with ports or apertures coinciding with 25 those of the fixed disc A may be arranged between the disc A and the disc C.

What I claim as my invention and desire to protect by Letters Patent is:—

In a bottle-filling machine embodying a 30 head having a snift conduit communicating with the atmosphere, a gas inlet conduit, a liquor inlet conduit provided with a valve, and a gas return conduit, and wherein the head carries a gas delivery and escape

pipe and a liquor delivery pipe, a valve for 35 controlling said conduits, said valve comprising a disk carried by said head and having a gas inlet port connected to the gas inlet conduit, a gas escape port connected to the gas return conduit, a gas outlet port 40 connected to the gas delivery and escape pipe, a snift port connected to the snift conduit, a liquor inlet port connected to the liquor inlet conduit, and a liquor outlet port 45 connected to the liquor delivery pipe, all of said ports terminating in the outer face of said disk, said disk also having an arcuate groove formed in its outer face and connected with said gas outlet port; a second disk 50 contacting with and adapted to oscillate relatively to said first-named disk, said second disk having in its contacting face a radial groove always opposite to and in communication with the arcuate groove of said first-named disk and adapted by oscillating movements of said second-named disk to be brought opposite to said gas inlet port, said gas escape port, or said snift port; said second-named disk also having a second groove formed in its contacting face 55 and adapted, when said radial groove is opposite said gas escape port, to register with and establish communication between the liquor inlet port and liquor outlet port of said first-named disk.

In testimony whereof I have hereunto set my hand.

ALBERT WOODALL SMITH.
